INTERNAL COMBUSTION HAMMER

Emmons R. Boddingtonhouse, Chicago, Ill., assignor
to Gas Tool Patents Corporation, Chicago, Ill.,
a corporation of Delaware.

Application August 13, 1934, Serial No. 739,553

9 Claims. (Cl. 123—7)

This invention relates to improvements in internal combustion hammers.

One of the objects of the invention is to provide a portable internal combustion hammer so constructed that the conduction of heat from the combustion chamber to the associated parts of the device is limited and controlled for minimizing the harmful effect of such heat upon the associated parts.

Another object of the invention is to provide a hammer having such a predetermined relationship between the relative weights of the parts, the spring load and the hardness of the parts as will ensure durability and most efficient operation.

Another object of the invention is to provide improvements in the cooling fin construction affording more rapid dissipation of heat and greater strength in the entire device.

Another object of the invention is to provide a construction assuring the device greater ruggedness and durability.

Other objects and advantages of the invention inherently possessed by it will become apparent upon a perusal of this specification.

In the drawings:

Fig. 1 is a vertical axial section through a device embodying the invention;

Fig. 2 is a plan view of the device;

Fig. 3 is a detail view in cross section through the cylinder and piston in the plane indicated at 3—3 in Fig. 1;

Fig. 4 is a side elevation of the device from a viewpoint ninety degrees removed angularly from that of Fig. 1, a portion of the fuel tank and carburetor being broken away in section;

Fig. 5 is an enlarged fragmentary detail in section through a portion of the fuel tank and carburetor;

Fig. 6 is an enlarged fragmentary detail in section in a different plane from the section of Fig. 5 showing the carburetor mixing valve;

Fig. 7 is a bottom plan view of the fuel tank and carburetor unit;

Fig. 8 is a side elevation, partly in section, showing a modified form of my invention; and Fig. 9 is an enlarged view showing the abutting relation of the return and cushioning springs.

The cylinder 8 is provided with cooling fins 9 which preferably extend in vertical planes radiating from its vertical center. It is preferably made of cast iron in accordance with the approved practice for cylinders. Its upper end is closed to provide a combustion chamber into which the usual spark plug 11 is introduced. A cap screw 55 10 and a washer 10^a having a flat side bearing

against one of the flat surfaces on the spark plug 11 will serve to prevent the spark plug from becoming unscrewed.

The castings employed in this device, with the exception of the cylinder casting, are preferably made of steel.

At the top of the fins 9 there is provided an annular shoulder 12 upon which rests a handle ring 13 to which the handles 14 are bolted. One of these handles serves as a conduit to receive the cable 15 which carries the electrical connections to the spark plug 11 and the timer hereinafter to be described.

The connection between the handles and the handle ring 13 is preferably effected through a heavy gasket 16 which insulates the handles from the heat developed in the cylinder casting. The joint between the cylinder casting and the handle ring, although not provided with any gasket, is in itself a means of heat insulation since any joint offers a high reluctance path to the conductance of heat.

At the lower end of the cylinder casting is the so-called lower unit 17 which closes the lower end of the cylinder and provides a bearing guide for 25 the anvil member 18, into the socketed end of which the tool 19 is received. The tool is guided in a fitting 19^a applied to the lower unit 17. Packing rings 18^a surrounding the anvil 18 serve to prevent escape of gases downwardly from the 30 sub-piston compression chamber 20.

It is important to note the location of the joint between the lower unit 17 and the cylinder casting. This joint is located relatively high on the hammer and is packed with a gasket 17^a to minimize heat conduction from the cylinder to the fuel tank and carburetor unit, which is supported from the lower unit 17 in a manner hereinafter to be described.

The handle ring, cylinder casting, lower unit and tool guide are held in assembled relationship by means of long tension bolts 21. Annular shoulders 21^b, above which these bolts are reduced in diameter, in connection with nuts 21^a firmly seat the unit 17 against the bottom of the cylinder. 45 A flat surface 21^c on each bolt fitting into corresponding recesses in the unit 17 prevent these bolts from turning. Surrounding the lower ends of the tension bolts are heavy springs 22 seated upon heads 23 and 24 and against the tool 50 guide 19^a as shown.

Just below the nuts 21^a the tension bolts are provided with reduced portions 21^d having diameters approximately one-half that of the lower ends of the bolts. By reason of the presence of

these reduced portions it is found that when the cylinder casting expands, due to heat during operation of the hammer, these bolts will stretch, particularly in the reduced portions 21^a, and will return to their original length when the casting becomes cool. Thus the unit 17 and ring 13 will always be held seated very firmly upon the cylinder casting.

When the tool or drill 19 is engaged with the work and the weight of the entire device rests upon it, the anvil 18 will be supported free from the bottom 25 of the recess in the tool guide. The tool guide itself will absorb the impact of the piston whenever the work does not absorb it through the tool 19. The resistance offered by the tool guide to the impact of the hammer under such conditions may be varied by substituting stronger or weaker springs 22.

The timer for producing the spark is housed in a sleeve 27 inserted into the cylinder casting and carries a reciprocable piston 28 on the inner end of which is mounted a cam follower roller 29. On the outer end of this piston is positioned a spring 31 seated against a shoulder on the plate 32 for holding the cam follower 29 against its associated cam. The upper end of the contact spring is insulated from the hammer by being clamped between two insulating washers, as shown. The lower end of contact 33 normally rests against a post 34 made of insulating material. A cam surface 35 is provided along the skirt of the piston 36.

When the timer piston 28 is moved outwardly by the cam 35 it strikes the spring 33 and grounds it on the frame of the hammer, whereupon the ignition spark is created.

The piston itself is provided with the usual compression rings 38 and preferably the piston 36 will be shrunk upon a striking portion 37 which preferably is separately heat treated to prepare it for the hard usage to which it is subjected.

The upper end of the piston is provided with a plurality of horizontal passages 39 which communicate with a recess 41 at one side of the piston. At the lower end of the downstroke of the piston this recess communicates with the lower end of the connecting chamber 42 while the top of the piston is simultaneously disposed somewhat below the top of the connecting chamber 42. At that instant communication is established between the combustion chamber 43 and the sub-piston compression chamber 20. The described communication is completed through the horizontal passages 39 and a plurality of vertical passages 44 disposed as shown.

The return spring 45 and the cushioning spring 46 are preferably wound in the same direction and have square ends which abut each other slightly below the top of the reduced portion of the anvil 18 as shown in Fig. 9.

Mounted on top of the device and extending downwardly through the top of the upper casting is a plunger 47 having an enlarged head 48 and a small head 49 at its lower end which extends into the top of the combustion chamber. A spring 51 resting upon the top of the casting and against the head 48, as shown, normally maintains this plunger in raised position. The plunger is employed for thrusting the piston downwardly when it is desired to start the piston in operation. By locating the spring 51 on top of the fins rather than upon the top of the combustion chamber it is thus separated from the

cylinder sufficiently to be shielded from temperatures that might adversely affect its temper.

The fuel tank which supplies the fuel for the combustible mixture is carried upon the device, extending part of the distance around the side of the device. The tank, designated 52, is supported wholly upon the lower unit 17 of the apparatus, and by reason of its location low on the device and because of the gasket 17^a opposing downward conduction of heat, the fuel tank is found to be sufficiently shielded from heat produced by operation of the hammer to avoid any harmful evaporation of the liquid fuel carried in the tank. The gasket 17^a and the joint in which it is disposed together serve as a very efficient combined heat insulator. The lower unit is provided with a boss 53 upon which is fitted an appropriately shaped part 54 of the fuel tank. Bolts 55 serve to firmly unite the tank to the boss 53. A U-bolt 56 connected with the fuel tank and embracing the sides of the device, as shown, assists in securing the tank in position.

Carried by and partially contained within the fuel tank is a carbureting device which includes a screened air inlet 57 opening into a passage 58 for admitting air under suction created in the sub-piston compression space during the upstroke of the piston. The air is admitted through a check valve 59 which is normally held seated by a spring 61. Suction lifts the valve 59 and as the air flows past it a charge of liquid fuel is drawn through a strainer 62 positioned within the bottom of the fuel tank through a passage 63 past a needle valve 64, thence through the regulating nozzle 65 into the air stream. The combustible mixture then flows into the passage 66, thence into a vertically extending recess 67 in the unit 17 adjoining the return spring 45. This recess delivers the combustible mixture into the sub-piston compression space wherein it is compressed on the downstroke of the piston and thereafter transferred through the transfer chamber 42 upwardly into the combustion space 43 at the time the piston reaches the lower limit of its travel. The recess 67 cut back into the cylindrical passage in the lower unit 17 prevents the convolutions of the springs from interfering with the travel of this gas.

It is particularly worthy of note that the valve 59 and its mounting and the needle valve 64, its mounting and the strainer intake 62 are unitarily mounted in a block 68 which is removable and replaceable as a unit and which when secured to the bottom of the fuel tank constitutes a unit with the fuel tank whereby the composite unit may readily be removed from the device and replaced. A cover 69 (see Fig. 5) is employed to surround the lower end of the valve 59.

The vertically extending heat radiating fins 9 add considerable strength to the entire device 60 without unnecessarily increasing the weight thereof. Vertical channels between these vanes enable the heated air to rise and escape readily. The handle supporting ring being mounted at the top of these vanes and having apertures therethrough, as shown in Fig. 1, is itself maintained fairly cool. The plunger supporting spring 51 being supported above the rest of the structure is kept cool and its long life thereby assured.

The fuel tank having no direct mechanical connection with the cylinder casting is well protected from heat and the joint and packing at 17^a further aids in insulating the heat from the tank. The shape of the tank, as illustrated in Fig. 1, showing its inner walls inclined away from the 75

sides of the cylinder casting, is a further aid in saving the fuel tank from becoming too hot.

A cover 71 for the filling opening for the fuel tank is provided, as shown.

5 For returning the piston it is preferred to use the combined action of the springs 45 and 46 although one spring alone or more than two springs might be used.

10 The battery and coil for supplying the ignition current will be connected with the cable 15 and supported either apart from the hammer or upon it.

15 By delivering the freshly formed fuel mixture into the lower end of the cylindrical channel in the unit 17, the adjoining portions of the springs are cooled and their heat is thereby carried away by the combustion charge. The channel 67 is provided to prevent these springs from blocking the efficient delivery of the fuel but should not 20 be so wide as to permit the springs to enter thereto. The upper end of the return spring is cooled by the gases flowing into the vertical passages 44, while the remainder of this spring is exposed to cooling by the gases in the middle portion of 25 the sub-piston compression space.

30 In the operation of the device the piston is returned after the power stroke by the combined action of the springs 45 and 46 and the rebound which occurs from the impact of the striker portion of the piston upon the reduced portion of the anvil. In order that the anvil and hammer may have the necessary durability and may cause 35 the desired rebound, they should each have a minimum hardness of 60 scleroscope.

35 The maximum spring load referred to herein is that force in pounds required to force the piston manually down into contact with the anvil.

40 I have discovered that the maintenance of a predetermined ratio between the piston weight, the scleroscope hardness of the striker portion of the piston and of the anvil, and the maximum spring load of the return springs is essential to efficient operation of the hammer as a whole. The scleroscope hardness of the striker portion 45 and the anvil preferably should not fall below a minimum of 60 scleroscope. The maximum spring load in pounds of the return springs should not exceed thirty times the weight in pounds of the piston. When these ratios are maintained, 50 the device will have the rapidity of action required for its work and excessive vibration will not be imparted to the entire device.

55 While the piston is shown as comprised of two parts assembled permanently together, it is contemplated that the striker portion may be originally cast or otherwise formed integrally with the upper portion of the piston.

Fig. 8 shows a modified form of my invention 60 which has the same internal operating parts as the preferred form shown in Fig. 1, but involves a different external assembly of the cylinder, the anvil housing and the handles. In the modified form the lower end of the cylinder is clamped directly to the upper end of the anvil housing 65 while the handle ring is supported wholly on the long outside tension bolts rather than upon the cylinder fins. This modified form of the hammer comprises a cylinder 81 on the outer surface of which is a plurality of outwardly and 70 longitudinally extending fins 82. The upper ends of these fins are formed as shown to pass within a handle ring 83, this ring not being supported upon the fins but merely lightly contacting the edges thereof. The handle ring 83 is 75 shaped and constructed exactly like the handle

ring of Fig. 1, having insulating strips 84 and handles 85.

At opposite sides the handle ring is provided with lugs, one of which 86 is shown, through which the outside tension bolts pass. The bolt 81, shown in Fig. 8, is provided with a shoulder just below the lug, upon which the lug seats, and a nut 88 clamps the two together. The lower end of the tension bolt 87 extends through the flange 89 on the cylinder casting and through 10 the wall of the anvil housing or lower unit 91. It will be understood that a piston and an anvil, together with return springs similar to those shown in Fig. 1, are employed in this modified form of the invention. The rod 87 extends upwardly through the lower unit 91, passing into a boss 92 at which point is located a shoulder 93 on the rod, together with a corresponding recess in the lower unit and a flat surface 94 on the side of the rod cooperating with a corresponding 20 flat sided recess to prevent turning of the tension bolt. A pin 90 may be driven through each bolt 87 just above the flange 89 to prevent downward movement of the bolt.

25 A tool guide 95 is yieldably supported on the tension bolt 87 and its mate on the opposite side, as in the preferred embodiment. One of the compression springs 96 is shown resting against the nut 87 and a boss 98 on the tool 30

35 In order to secure the cylinder casting and the lower unit firmly together without undue conduction of heat from the cylinder to the anvil housing, I have provided a pair of bosses 98 and 99 at the lower marginal portion of the cylinder casting and cooperating bosses 101 and 102 on the anvil housing. Short bolts 103 and 104 passing through these bosses secure the two parts firmly together. A heat insulating gasket 105 at 40 the juncture of these two parts prevents any unduly extensive conduction of heat from the cylinder casting to the anvil housing. This precaution is important in order that the fuel tank, which is supported wholly on the anvil housing, as is the case in the preferred embodiment, may 45 be protected from the heat generated by the operation of the hammer. The lower end of the cylinder, where the lugs are located, naturally is kept relatively cool by reason of the fuel mixture flowing through the sub-piston compression 50 space within the lower end of the cylinder.

55 During use the cylinder casting will become heated and will naturally lengthen but this tendency to lengthen is not in any way restricted by the handle ring, as the fins may slide upwardly therewithin and return equally easily when cooling. There is, therefore, no increase or decrease of tension upon the tension bolt 87 and its counterpart on the other side of the hammer by reason of expansion or contraction of the 60 cylinder. Therefore the reduction in area of the tension bolts, as shown in Fig. 4, is not necessary in this embodiment. In fact, these tension bolts may well be made much more sturdy as they must sustain wholly or nearly so the thrust 65 imparted between the lower end of the hammer and its handles.

70 It should be understood that the constructions herein shown and described have been selected for the purpose of illustrating the invention, and not for the purpose of indicating its limits. Various modifications of the invention and its parts may be made without a departure from the scope of the invention, particularly as it is defined in the appended claims.

I claim:

1. In an internal combustion hammer having a cylinder and an anvil housing therebelow fixedly secured thereto, a tool guide below said housing, longitudinally extending fins on the cylinder rising thereabove, a pair of handles, and means yieldably supporting the tool guide below the housing and rigidly and solely supporting the handles independently of and above the cylinder arranged to avoid interference with expansion and contraction of the cylinder.
2. In an internal combustion hammer having a cylinder and cooling fins thereon extending outwardly therefrom longitudinally of the cylinder to a point above the cylinder, an anvil, an anvil housing below the cylinder, a tool guide below said housing, a handle ring seated upon the upper ends of said fins above the cylinder and constructed to permit air circulation there-through between the fins, and means cooperating with said ring and tool guide for retaining said ring, cylinder, anvil housing, and tool guide in assembled relation.
3. The combination of a cylinder and a spring 25 returned piston therein, a separable lower unit seated against the lower end of said cylinder and insulated therefrom, a fuel tank supported on said unit and an anvil carried by the unit, a tool guide seated against the inner side of the unit 30 for receiving impact from the anvil and yieldably thereunder away from said unit, cooling fins on said cylinder extending outwardly therefrom longitudinally of the cylinder and extending thereabove, a handle ring supported on the top of said fins near their outer extremities so as to permit circulation of air between said fins and through said ring, and means cooperating with said ring for rigidly supporting said unit and yieldably supporting said tool guide.
4. In an internal combustion hammer having a cylinder and a spring return piston therein, an anvil housing at the lower end of said cylinder, heat insulating means disposed between said cylinder and housing, radiating fins on the cylinder projecting radially therefrom and extending longitudinally thereof above the upper end of said cylinder, a handle supporting member mounted upon the top of said fins near the outer extremities thereof so as to permit air flow through said member, a tool guide below said housing, and means connected to said member for rigidly supporting said housing upon the cylinder and yieldably urging the said tool guides against the lower end of said housing.
5. An internal combustion hammer comprising a cylinder, a piston reciprocable therein, radially disposed fins extending longitudinally of said cylinder and beyond the upper end thereof, a plunger rod guide located above the cylinder and coaxially therewith, the upper ends of the spaces between the fins being open to provide for air circulation around the cylinder and guide, a plunger rod extending through said guide and the cylinder head and having at its upper end provision for hand

operation of the rod, and a spring interposed between the upper ends of said fins and the hand provision on the rod whereby said rod is yieldably retained in raised position.

6. An internal combustion hammer comprising 5 a cylinder, a spring returned piston reciprocable therein, cooling fins extending radially from the cylinder and projecting longitudinally thereof above the upper end of the cylinder, a starting plunger extending from within the cylinder to 10 a position above the top of said fins, a plunger guide disposed axially of said cylinder at the upper end of the fins, a handle ring disposed circumferentially of the fins at their upper ends so as to leave unobstructed air passages defined by 15 said fins, said guide and said ring, and a spring mounted above said fins in the path of said air flow for holding said plunger in raised position.

7. An internal combustion hammer comprising 20 a cylinder provided with cooling fins extending radially outwardly therefrom and projecting longitudinally of the cylinder above the upper end thereof, handle supporting means, and a plunger guide carried by said fins above said cylinder and constructed to afford unobstructed passages between 25 said fins to facilitate unrestricted upward flow of air between said fins.

8. An internal combustion hammer comprising 30 a cylinder equipped with radially projecting longitudinal disposed radiating fins extending above the upper end of the cylinder, an anvil housing at the lower end of said cylinder, a tool guide abutting the lower end of said housing, a handle ring seated upon the upper ends of said fins, tie rods extending between adjacent fins 35 and through said ring, said housing, and said tool guide, said rods having shoulders engaging said housing and nuts threaded thereon above said ring whereby said ring, cylinder, and housing are rigidly clamped together, said rods being of reduced diameter adjacent to the cylinder to facilitate longitudinal expansion and contraction thereof in conformity with variations in the cylinder length whereby rigidity of the assembly is maintained without injury to the said rods, and 40 springs interposed between the headed lower ends of said rods and said tool guide to yieldably hold said guides against said housing.

9. An internal combustion hammer comprising 45 a cylinder, a piston therein, an anvil housing below the cylinder, the lower end of said cylinder and the upper end of said housing being provided with aligned bolt-receiving lugs, bolts cooperating with said lugs to secure said cylinder and housing rigidly together, radiating fins projecting radially from and extending longitudinally of said cylinder, a handle ring loosely surrounding the upper portions of said fins, and means extending upwardly from said housing whereby said ring is supported independently of said fins so as 55 to be unaffected by longitudinal expansion of said fins.

EMMONS R. BODDINGHOUSE.
